Inventor.

Michael A. Kishell

By Mason Fenwick Lawrence,
Attorney

UNITED STATES PATENT OFFICE.

MICHAEL A. KISHELL, OF DICKSON, PENNSYLVANIA.

PAPER-HANGING MACHINE.

Application filed June 24, 1922. Serial No. 570,580.

To all whom it may concern:

Be it known that I, MICHAEL A. KISHELL, a citizen of the United States, residing at Dickson, in the county of Lackawanna and State of Pennsylvania, have invented certain new and useful Improvements in Paper-Hanging Machines; and I do hereby declare the following to be a full, clear, and exact description of the invention, such as will enable others skilled in the art to which it appertains to make and use the same.

This invention has for its object to provide a paper hanging machine, the machine being so constructed as to facilitate removal of the paste roller, there being also provided trimming devices for trimming the edges of the paper and paper severing means. It is a further object to provide a compact and efficient machine which can be manufactured at low cost. Other objects and features of novelty of the invention will appear from the detailed description taken in connection with the accompanying two sheets of drawings forming part of this specification.

Referring to the drawings—

Figure 1 is an end elevation of the improved machine;

Fig. 2 is a front elevation of the same, parts being shown in section;

Fig. 3 is a vertical transverse section;

Fig. 4 is a plan of the machine;

Fig. 5 is a section on line 5—5 of Fig. 3, and

Figs. 6, 7 and 8 are fragments illustrating details.

In the drawings, 10 indicates a shaft for supporting a roll of wall paper 11, said shaft being mounted in side standards or supports 12 comprising the frame of the machine. The standards are made in two parts *a* and *b* for purposes hereinafter appearing.

13 is a shaft extending between the standards 12, said shaft being mounted in the lower portion *b* of the frame. This shaft supports a paste roller 14 which dips into paste contained in a receptacle secured to the frame members *b*.

Fixed on shaft 13 is a beveled gear 15 and fixed on shaft 10 is a similar gear 16. 17 is a vertical shaft mounted in brackets 18, said shaft having affixed thereto beveled gears 19 and 20 meshing with gears 16 and 15 respectively. It will now be understood

that when shaft 10 is rotated shaft 13 will also be rotated by means of said gearing.

21 is another shaft mounted in the frame, and 22 is a beveled gear fixed to one end of said shaft. 23 is a gear fixed to shaft 17 and meshing with gear 22. Shaft 21 is, therefore, rotatable along with shaft 10.

24 indicates a pair of paper guiding members in the nature of rollers mounted between the frames 12. These rollers are mounted on either side of the top of roller 14 so as to cause the wall paper when drawn beneath said rollers, to contact with the top of the paste roller for an obvious purpose. It may be pointed out at this time that shafts 10, 13 and 21 are in substantially the same vertical plane.

25 is a brush which is adapted to force the paper against the wall diagrammatically indicated at W in Fig. 3. This brush is pivotally mounted on a rod 26 which is secured in brackets 12' extending from the upper end of the frame. The brush is removably mounted on said rod by means of clips 27. This arrangement enables the brush to be readily removed for cleaning purposes. The brush is provided with a handle 28 which extends laterally of the brush proper. The handle is adapted to be grasped by the operator and swung about its supporting shaft 26 as will be readily understood. However, if the roll of paper is of sufficiently large diameter, the handle may rest thereon during the operation of putting the paper on the wall.

29 indicates the bail-like handle by which the machine is supported during the operation of applying the wall paper. 30 indicates a bail handle which may be used for carrying the machine around.

The paste receptacle is indicated at 31 and as shown may consist of a sheet metal pan suitably secured to the side standards or parts *b* of the frame. This receptacle is provided with removable covers 31' to allow access to said receptacle.

The receptacle part *b* of the frame is pivoted to part *a* at 32 whereby part *a* can be swung about said pivot to permit the paste roller to be removed for cleaning. 33 indicates a latch and 34 a cooperating pin for securing the frame parts *a* and *b* in fixed relation. It may be pointed out at this time that, when the upper part of the machine is swung about the pivot 32, the gear 15 on

shaft 13 will separate from the bevel gear 20 on shaft 17.

Means for trimming the edges of the paper are also provided, these means constituting circular cutters 35 adjustably mounted on the shaft 21. These cutters co-act with the periphery of the roller 14 which forms a block or base against which the cutters re-act, it being recalled that the wall paper 10 is forced against the top of roller 14 by the cross rods 24. It will be further recalled that shaft 21 is continuously driven along with shaft 10 by the gear mechanism previously described.

15 In order to permit severance of a strip of paper after the same has passed over the roller 14, there is provided a straight edge knife 36. This knife has angular extensions 37 which are mounted loose on the shaft 21 20 to permit the knife to be rocked on said shaft. A spring 38 extending between said knife and frame 12 maintains the knife in the position shown in Figs. 3 and 5. The edge of the knife is preferably of saw-tooth 25 design to prevent slippage of the paper as will be readily understood.

In order to enable ready placement and removal of the roll of paper 11, the shaft 10 is removably held in the frame. 39 indicates a stub shaft which is mounted at the upper end of the spring element 39', this stub extending into the terminal end of the shaft 10 proper. The other end of shaft 10 is provided with an octagonal socket into 35 which is entered the stub shaft 10' which extends from gear 16, this stub shaft extending through the frame 12, (see Fig. 6).

40 In order to prevent rotation of the roll of paper on the shaft 10, there is provided suitable friction means. In the present instance, this means takes the form of axially projecting fingers 40 extending from the ends of a tubular section 41 constituting part of the shaft 10, said section having a 45 radial flange 42 from which said fingers project. These fingers are forced into one end of the roll as will be readily understood, (see Fig. 2).

50 In order to permit ready removal of the paste roller 14 from the receptacle part *b* of the machine, the same has been mounted therein in a novel manner. Said roller has a short or stub shaft 43 which has bearing in a shelf or ledge formed in the frame part *b* as clearly shown in Figs. 7 and 8. It will be noted that the adjacent ends of the frame parts *a* and *b* are rabbeted to form a firm connection therebetween. The other end of the roller is provided with an octagonal socket which receives the stub shaft 15 projecting from the gear 15, (see Fig. 7). It will be understood that reference numeral 13 indicated the roller shaft as an entirety.

60 The operation of the machine will now be briefly described. Assuming that the recep-

tacle 31 is filled with paste and that a roll of paper is mounted on the shaft 10, the free end of the latter is passed beneath the cross rods or rollers 24 and led upwardly in front of the brush as shown in Fig. 3. After the 70 free end of the paper has been attached to the wall, the machine is moved bodily downward, this movement causing the paper to unwind from the roll 11, and in so un winding it engages with the roller 14 to receive 75 paste as will now be readily understood. As the paper is being drawn over the top of roller 14 the circular cutters 35 function to trim the side edges of the same, it being remembered that shaft 21 is driven from shaft 80 10. When it is desired to sever the paper the knife 36 is pressed forwardly to perforate the paper whereupon the same can be readily severed as will be readily understood.

85 When it is desired to have access to the paste roller 14 for cleaning or otherwise, the latch 33 is released to permit tilting of the upper part of the machine about the pivot 32 as will now be readily understood. 90 As already indicated, the gear 15 separates from gear 20, this arrangement constituting in effect a releasable clutch member.

95 By reason of the fact that the paste roller 14 is positively driven by shaft 10, it is assured that paste will always be supplied to the paper as it is drawn over the roller. In rollers not positively driven it is often found that the roller ceases to rotate for one reason or another, and hence paste is not applied to the paper.

100 While I have described the invention with considerable particularity of detail, I desire it to be clearly understood that I intend no limitations except as may be defined by the 105 appended claims.

What I claim is:

1. In combination, a frame, a brush supported thereon, a shaft for supporting a roll of paper, a paste roller, a pair of paper guiding members one on each side of said roller so disposed that paper passed under said members will contact with the top of the paste roller, driving connections between said shaft and paste roller, and means permitting disengagement of said driving connections and bodily displacement of said paste roller relatively to said members.

110 2. In combination, a frame, a brush supported thereon, a shaft for supporting a roll of paper, a paste roller, a pair of paper guiding members one on each side of said roller so disposed that paper passed under said members will contact with the top of the paste roller, driving connections between 115 said shaft and paste roller, and circular paper cutters arranged above the paste roller and coacting therewith and driven from said driving connections.

120 3. In combination, a frame, a brush sup-

- ported thereon, a shaft for supporting a roll of paper, a paste roller, a pair of paper guiding members one on each side of said roller so disposed that paper passed under 5 said members will contact with the top of the paste roller, driving connections between said shaft and paste roller, circular paper cutters coacting with the paste roller, and a cutter-supporting shaft disposed 10 above said paste roller between said members, and driven from the said driving connections.
4. In combination, a frame, a brush supported thereon, a shaft for supporting a roll 15 of paper, a paste roller, a pair of paper guiding members one on each side of said roller so disposed that paper passed under said members will contact with the top of the paste roller, driving connections between 20 said shaft and paste roller, a straight-edge knife disposed above said idler rollers, a pair of circular cutters coacting with the paste roller, and a cutter-supporting shaft disposed below said knife and above said 25 idler rollers.
5. In combination, a frame, a brush supported thereon, a shaft for supporting a roll of paper, a paste roller, a pair of paper guiding members one on each side of said 30 roller so disposed that paper passed under said members will contact with the top of the paste roller, driving connections between said shaft and paste roller, a straight-edge knife disposed above said members, a pair 35 of circular cutters coacting with the paste roller, and a cutter-supporting shaft disposed below said knife and above said members, said knife being pivoted on said cutter-supporting shaft, and said shaft being 40 driven by said driving connections.
6. In combination, a frame comprising two side members, a roll-of-paper-supporting shaft mounted in said frame, a paste roller mounted at the lower end of the 45 frame, said lower end constituting a sectional part of said frame, driving connections between said shaft and roller, a pair of paper guiding members extending parallel to the paste roller on either side of the 50 top of the same slightly below said top, said sectional part of the frame being movable to permit removal of the paste roller therefrom.
7. The combination as in claim 6, said sectional part having a paste receptacle secured thereto.
8. In combination, a frame comprising two side members, a roll-of-paper-supporting shaft mounted in said frame, a paste 55 roller mounted at the lower end of the frame, said lower end constituting a sec-
- tional part of said frame, driving connections between said shaft and roller, a pair of paper guiding members extending parallel to the paste roller on either side of the 60 top of the same slightly below said top, said sectional part being hinged to said frame and carrying a paste receptacle.
9. In combination, two spaced supports each of which comprises two parts hingedly connected, a paste roller removably mounted across said supports at the joinder of said parts, a roll-of-paper-supporting shaft mounted at the upper ends of said supports, and a separable driving connection between 65 said shaft and roller.
10. In combination, two spaced supports each of which comprises two parts hingedly connected, a paste roller removably mounted across said supports at the joinder of said parts, a roll-of-paper-supporting shaft mounted at the upper ends of said supports, a separable driving connection between 70 said shaft and roller, a pair of paper guiding members mounted in said supports in fixed relation to said shaft, a pair of circular cutters coacting with the paste roller, a cutter-supporting shaft disposed between said 75 rods, and a knife mounted above said cutters.
11. In combination, a frame, three shafts mounted therein in substantially the same vertical plane, one of said shafts constituting a paste roller, a pair of paper guiding members mounted on either side of said 80 plane adjacent the top of the paste roller, means supporting said roller in displaceable relation to said other shafts, a pair of circular cutters carried by one of said shafts and coacting with the paste roller, the upper 85 shaft of the series being adapted to support a roll of paper, and a brush pivotally hung from said frame adjacent the upper shaft.
12. The combination as in claim 11, and a tiltable knife disposed in the frame above 90 the circular cutters.
13. In combination, two upright supports, a pair of stub shafts mounted in the supports at the upper and lower ends thereof, gears carried by said shafts, a driving connection between said gears, a roll-of-paper-supporting shaft removably connected to the upper of said shafts, a paste roller removably connected to the lower of said shafts, and a brush pivotally supported by said supports.
14. The combination as in claim 13, each of said supports constituting two parts, the lower part being hingedly connected to the other part and mounting the paste roller.
- In testimony whereof I affix my signature.
- MICHAEL A. KISHELL.
